COVER RACK

Sven V. Swanson, Hartford, Conn.

Application December 6, 1932, Serial No. 645,903

4 Claims. (Cl. 211—41)

My invention relates to that class of holders or racks employed for retaining kitchen utensils, and particularly pot covers, in place, and an object of my invention, among others, is the provision of a rack of this type that shall be simple in construction, comparatively cheap to produce, and one adapted for holding articles of various sizes and to retain them within a minimum amount of space.

10 One form of a rack embodying my invention and in the construction and use of which the objects herein set out, as well as others, may be attained is illustrated in the accompanying drawing, in which—

15 Figure 1 is a front view of my improved rack within which a number of pot covers are located.

Figure 2 is an edge view of the same.

Figure 3 is a view in central lengthwise section with the pot covers removed.

20 Figure 4 is a view in section on a plane denoted by the dotted line 4—4 of Fig. 1.

In the accompanying drawing the numeral 5 denotes the back or base of my improved rack that may be constructed of any suitable material, preferably sheet metal, said back comprising a flange 6 of a width merely to receive screws for securing frames in place.

These frames 7 are preferably formed of wire, in the structure herein shown, four of these frames being employed and increasing in width from the top to the bottom of the back 5, the latter being tapered from a small dimension at the top to a larger width at the bottom and as shown in Fig. 1. Each frame comprises a side rail 8 at each side of the frame, said rails each having an eye 9 at its end to receive a screw bolt 10 projected through the flange 6, and as shown in Fig. 3 of the drawing. Each frame has a V-holder 11 located inwardly of the side edges of the back and on opposite sides of a line extended centrally from the top to the bottom of the back, the inner side parts of the V-holders being united by a U-bend 12. The wire forming a frame is extended backwardly from the apex of the V-shaped holders in two strands to form rests 13, said wire being bent at the ends of the rests into eyes 14 to receive fastenings 15 preferably in the form of screw bolts.

The side rails 8 and the outer branches of the V-holders are joined by a front rail 16, the side rails 8 being of a length to locate the front portion of each frame comprising the V-holders and front rails a proper distance from the back to receive a number of pot covers 17 or other similar kitchen utensils, and the V-holders are

adapted to receive the knobs 18 of the pot covers thereby reducing the space required for the bodies of the covers, the knobs projecting through the front of the frame, and as shown in Fig. 2 of the drawing.

In use the covers are placed with their bottom edges seated upon the rests 13 and with the knobs 18 projecting through the spaces between the branches of the V-holders, and the covers of larger sizes may rest with their bottom edges upon both of the rests 13 appurtenant to a single frame with the knobs projecting through the space between the inner branches of the V-shaped holders, and as shown in Fig. 1 of the drawing. It will thus be seen that the covers or similar utensils may be arranged in various ways so that a frame of minimum size will be capable of receiving a maximum number of utensils, said frame being formed of a single piece of wire bent to shape.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim:

1. A cover rack including a back and a front inclined upwardly and forwardly from said back and comprising a frame formed of a single piece of wire and including a plurality of V-holders spaced apart at their apexes and terminating in 35 backwardly extending side rails at the ends opposite said apexes thereby positioning said frame at an angle to the plane of said back, eyes formed at the ends of the side rails, fastenings 40 projecting through said eyes to secure the frame to the back, and means at adjacent apexes to conjointly support covers.

2. A cover rack including a back and a front inclined upwardly and forwardly from said back and comprising a frame formed of a single piece of wire and including a plurality of V-holders having their apexes spaced apart to conjointly support a cover, rests extending inwardly from the apexes of the V-holders and terminating in 45 eyes, side rails extending from the outer members of the outer V-holders and terminating in eyes, and fastenings extended through adjacent eyes to secure the frame to the back.

3. A cover rack including a back and a front inclined upwardly and forwardly from said back 55

and comprising a frame formed of a single piece of wire including a plurality of V-holders spaced apart at their apexes and terminating in side rails at the ends opposite said apexes, eyes formed at the ends of the side rails, a U-bend joining the branches of adjacent holders, rests extending from adjacent apexes of the V-holders and spaced from the back to conjointly serve as a support for covers, eyes formed at the ends of said rests, and fastenings extended through said eyes to secure the frame to the back.

4. A cover holder including a back tapered from its bottom to its top end, a series of racks

disposed longitudinally along said back on the front face thereof, each rack being of a length equal to the width of the base at which the rack is located, each rack being formed of a single piece of wire bent to shape and including V-holders spaced apart at their apexes and terminating in side rails, eyes formed at the ends of the side rails, rests extending from the apexes of the V-holders, eyes formed at the ends of said rests, and fastenings extended through said eyes to secure the racks in place.

SVEN V. SWANSON.
